UNITED STATES PATENT OFFICE.

ROBERT C. LEPPERT, OF CHICAGO, ILLINOIS.

CONCERTINA OR ACCORDION.

Application filed February 10, 1926. Serial No. 87,335.

This invention has relation, generally, to improvements in concertinas or accordions, or that class of musical instruments in which extensible bellows are employed to produce sound by the action of the wind or air on reeds of various sizes, and particularly, to a valve and its actuating mechanism, for controlling the passage of air to and from the reeds and through the tremolo boxes.

10 The principal object of my present invention is to provide a musical instrument of the above named type, which shall be of high efficiency in its operation, and with its parts especially constructed, arranged 15 and combined, with respect to a valve and its actuating mechanism, employed for controlling the passage of air to and from the reeds of the instrument and through the tremolo boxes thereof, so as to attain musical 20 notes and combination of notes, of a more desirable character than has heretofore been produced by instruments of a like class.

The invention also has as one of its objects, means for the very nice or accurate adjustment of the actuating mechanism of said 25 controlling valve.

Furthermore, another object of the invention is, to so construct and arrange the push pin of said actuating mechanism that 30 it will not be accidentally operated by the movement of the lever which controls the valve for the in-take of air, or by the manipulation of the other parts of the instrument.

35 A still further object of the invention is, to provide simple and efficient means for the guidance of one of the members of the said actuating mechanism and also for the adjustment of said member in order that another part of said mechanism may be adjusted with respect to the controlling valve.

Various other objects and advantages of the invention will be disclosed in the following description and explanation, which will be more readily understood when read in conjunction with the accompanying drawings, which serve to illustrate an embodiment of my invention, it being understood that changes and modifications may be resorted to without a departure from the spirit of the invention, so long as they fall within the scope of the appended claims.

In the drawings—

Fig. 1, is a view in elevation of the end of the end-box located at the melody end of the instrument, facing the end-box at the other end of the instrument, showing tremolo valves, and my improved controlling valve mounted on its face.

Fig. 2, is a vertical sectional view taken on line 2, 2, of Fig. 1, as indicated by the arrows.

Fig. 3, is a similar view taken on line 3, 3, of Fig. 1, looking in the direction indicated by the arrows.

Fig. 4, is a like view taken on line 4, 4, of Fig. 1, looking in the direction of the arrows, said view showing the controlling valve and its actuating mechanism.

Fig. 5, is a transverse view taken on line 5, 5, of Fig. 4, as indicated by the arrows.

Fig. 6, is an inner face view of the outer wall of the end-box at the melody end of the instrument, taken on line 6, 6, of Fig. 4, showing in detail, the means for fastening the push pin in its retracted position and

Fig. 7, is a plan sectional view taken on line 7, 7, of Fig. 4, as indicated by the arrows.

Corresponding numerals of reference, designate like parts throughout the different views of the drawings.

It will be understood that in the drawings, only such parts as are concerned with the controlling valve and its mechanism for the passage of air to and from the reed box is shown, and that the other parts which operate in a manner well understood in the art, are omitted. The end-box which carries the reeds, the lever for the in-take of air, the hand strap, and other parts, and located at the melody end of the instrument, is indicated by the reference numeral 10, and is shown in the drawing in about the position it will occupy when the instrument is being played. This box has mounted on its inner wall 11, or wall adjacent the other end-box (not shown) a bellows 12, of the ordinary construction and in the usual manner, which bellows is of an extensible nature and is fastened at its other end to the end-box (not shown). The wall or partition 11, is provided with three elongated openings 13, 14, and 15, located in parallelism

with one another, as shown in Fig. 5, of the drawing. These openings are covered by means of a screen 16, fastened to the front surface of the wall 11, or that surface thereof, adjacent the hand strap 17, on the front wall of the said end-box, for the purpose of keeping out foreign matter and dust. Each of the openings 13 and 14, is surrounded by a tremolo box 18, located on the rear surface of said wall. One of these tremolo boxes 18, is inclined downwardly towards the wall 11, while the other of said boxes is inclined upwardly from said wall at its rear surface, as is clearly shown in Figs. 2 and 3, of the drawings. The box 18, with the upwardly and rearwardly inclined wall, is provided in said wall with an opening 19, said opening being covered by a screen 20, for a well known purpose. Hinged to the inner surface of this rear wall just above its opening 19, is a valve 21, which carries on its lower end a flexible arm 22, on the free end of which is mounted a weight 23, to give vibration to the valve 21, when the same is operated. This valve and the port or opening 19, which it closes may be provided with cushioning material on their adjacent portions to make a close fit of the valve, as is well known. The other valve box 18, has in its downwardly and rearwardly inclined wall an opening or port 24, which is closed by means of valve 25, hinged at its upper end to the rear surface of its inclined wall at a distance above the opening 24, so that said opening will approximate the lower end of the valve 25, as shown. The latter named valve is provided with a resilient arm 22, secured to the lower end of the valve, and said arm is provided with a weight 23, as in the other valve, and for the same purpose.

The opening 15, in the wall 11, lies between the openings 13 and 14, and in parallelism therewith, as clearly shown in Fig. 5, of the drawings. This opening or port 15, is closed by a controlling valve 26, which extends vertically with respect to the end-box 10, when the instrument is being played, and is hinged at its lower end to the wall 11, just below the lower end of the port 15, therein. The valve 26, is located on the outer or rear surface of the wall 11, and has a plate on its front surface, and said plate is provided with a projection or boss 28, for screw threaded engagement with one prong 29, of an elbow-shaped member 30, of the actuating mechanism for said valve. The other and upwardly extended arm 31, of this member, is provided with a pair of longitudinally spaced set screws 32, which screws are employed to adjust one end of a link 33, to the arm 31, for it will be seen and understood by reference to Figs. 4 and 5, of the drawings, that the link 33, is provided near one of its ends with a slot 34, through

which the screws 32, are extended and screwed into suitable openings in the arm 31, of the above mentioned elbow member. The upper or other end of the link 33, is provided with an open ended slot 35, which slot receives the guide 36, secured transversely on the upper part of the end-box 10, by which means and arrangement it is obvious that the link 33, can be freed from the guide 36, by loosening the screws 32, and sliding the link 33, downwardly, when it is apparent the elbow member 30, can be turned with respect to the boss 28, so as to accurately and nicely adjust the elbow member with respect to the valve 26, so that a most efficient closure for the opening 15, will be afforded. After this adjustment has been made, the link 33, may be slid upwardly so as to engage the guide 36, as is apparent. The valve 26, is normally held in its closed position by means of a bow spring 37^a, secured at its lower end to a block 38, mounted and secured on the wall 11, below the lower or hinged end of the valve and rests, as shown, on the rear surface of said valve.

It will be observed by reference to Fig. 4, that the link 33, of the controlling valve actuating mechanism, extends at its upper end very close to the top wall of the end-box 10, and normally assumes a position in parallelism with the reed board 37, upon which the reeds (not shown) are mounted. Between the upper part of the board 37, and the front wall of the end-box 10, is mounted on said box, a depending bracket 38, which has an opening in its lower portion for the reception and operation of the reduced portion 39, of a push pin 40, which pin extends forwardly through an opening 40^a, in the front wall of the end-box 10, located in the upper part of said wall and near one side of the lever 41, which lever is used for operating the air in-take valve 42, through the medium of connections 43 and 44, which latter connection passes over a pulley 45, mounted on a bracket 46, secured to the bottom wall of the end-box 10, and is secured to said valve. The other connection 43, extends through the upper wall of the end-box 10, and has a head 47, on its outer end for engagement with the slotted end of said lever. By the proper manipulation of the lever 41, it is evident that the valve 42, will be opened for the passage of air through the port 42^a, which port is provided in one side of said end-box.

Extended through suitable openings in the upper portion of the board 37, and a plate 48, secured on the front surface of said board directly in front of the upper portion of the link 33, is a plunger rod 49, which has on its forward end a disk like head 50, against which disk the end of the reduced portion 39, of the push pin rests. The other end of the plunger rod 49, is provided with

a small head 51, which normally is slightly separated from the link 33, but is employed to contact with the upper portion of said link, when the push pin is pressed inwardly for the purpose of opening the valve 26, and thus allowing the free passage of air through the port 15, and at the same time, causing the valves 21 and 25, of the tremolo boxes 18, to remain closed. A spring 52, is coiled around the plunger rod 49, between the disk 50, and the apertured plate 48, and normally holds the plunger rod in a retracted position forwardly, as well as, the push pin 40, in its normal position.

As before stated, the push pin is located in an opening 40^a, in the front board of the end-box 10, and aligns with the plunger rod. In order to hold the push pin 40, in the position it will occupy when the valve 26, is opened, said pin is provided on one of its sides with a shoulder 53, which, when the pin is pressed inwardly said shoulder will engage a plate 54, secured to the inner surface of the front wall of the end-box 10, at the side of the opening 40^a, adjacent the shoulder 53. It will thus be understood, that in order to release the push pin 40, from the plate 54, it will be only necessary to push said pin slightly in a transverse direction with respect to the longitudinal axis of the instrument, and that by this arrangement there will be little or no danger of the push pin being accidentally operated when the lever 41, is depressed in order to open the in-take valve 42, which is held in a closed position by means of a spring 43^a, secured at one of its ends to the upper portion of the end-box 10, just above the hinge of the valve 42, for the in-take 42^a, of air.

From the foregoing and by reference to the drawings, it will be clearly seen and understood, that by extending and retracting the bellows and operating the lever controlling the in-take of air, it will pass from the opening 42^a, into the bellows, and from thence through the opening 15, when the valve 26, is opened, without producing any except the ordinary effect on the reeds. By closing the valve 26, which controls the opening 15, in the wall 11, which can be done by releasing the shoulder 53, of the push pin 40, from the plate 54, thus permitting the spring 37^a, to automatically close said valve, it is apparent that the current of air will be caused to flow through the tremolo boxes 18, in which operation the vibratory valves 21 and 25, will be caused to open and vibrate, thus producing tremolo notes or tones. When it is again desired to open the valve 26, it is apparent that this may be done by pressing the push pin 40, inwardly so as to cause the plunger rod 49, to contact with and push rearwardly the link 33, and the elbow arm 30, which is adjustably connected to said valve, in which operation it will be un-

derstood, that the guide 36, will co-operate with the slotted end of the link 33, so as to cause the parts to move with accuracy or precision. When the push pin shall have thus been pressed inwardly, it is obvious that its shoulder 53, will engage the plate 54, and that by reason of its connection with the valve 26, will hold the same open until its shoulder is released, when the bow spring 37, will automatically close the valve and cause the pin to assume its normal position. By arranging the shoulder 53, on one side of the push pin and the plate 54, for its engagement near the latter, it is apparent that on the inward pressure of the lever 41, there will be no liability in accidentally operating the push pin.

Having thus fully described the invention, what I claim as new and desire to secure by Letters Patent is—

1. In a musical instrument of the class described, the combination with an end-box, of a bellows secured to one end thereof, a wall located between the bellows and said box having an air-passage-way therein and an opening on each side of said way, a controlling valve hingedly mounted on the rear portion of said wall to close said air-passage-way, means to automatically close said valve and means for manually opening the same, said last named means consisting of an elbow shaped member having one of its arms adjustably connected to the said valve, a link longitudinally adjustably secured to the other arm of said member and having at its free end an open ended slot, a guide mounted longitudinally on the inner surface of the top of the instrument to co-act with the slot of said link for guiding the same in its movement, a spring actuated plunger rod mounted longitudinally with respect to the instrument in the said box for contact with said link, and a push pin mounted in the front wall of said box in alignment with the plunger rod and extended through said wall, said push pin having means to retain it in retracted position, said last named means being located at one side of the push pin to prevent its accidental operation when other parts of the instrument are manipulated.

2. A musical instrument of the class described including a partition across the end box of said instrument and having an air passage-way therein, a controlling valve hingedly mounted on the rear portion of said wall to close said air passage-way, means to automatically close said valve and means for manually opening the same, the last named means consisting of an elbow shaped member having one of its arms longitudinally slotted and its other arm adjustably connected to the said valve, a link longitudinally adjustable in said slot and having at its free end an open ended slot, a guide mounted on the inner surface of the top of

the instrument box to co-act with the slot of said link for guiding the same in its back and forth movement, a spring actuated plunger rod mounted longitudinally with respect to the instrument in the said box for contact with said link, and a push pin mounted in the front wall of the instrument box in alignment with the plunger rod and ex-

tended through said wall, said push pin having means to retain it in retracted position 10 said last named means being located at one side of the push pin to prevent its accidental operation when other parts of the instrument are manipulated.

ROBERT C. LEPPERT.
